UNITED STATES PATENT OFFICE.

LYNN B. CASE, OF HUDSON FALLS, NEW YORK, ASSIGNOR TO STANDARD WALL PAPER CO., OF HUDSON FALLS, NEW YORK, A CORPORATION OF NEW YORK.

UNIT DRIER.

Application filed October 31, 1922. Serial No. 598,171.

To all whom it may concern:

Be it known that I, LYNN B. CASE, a citizen of the United States, and a resident of Hudson Falls, in the county of Washington and State of New York, have invented a new and Improved Unit Drier, of which the following is a full, clear, and exact description.

This invention relates to a drying apparatus for removing moisture from materials after the same have been subjected to a coating operation, and has to do particularly with an improved unit drier for wall paper in which the same is arranged in festoons on a traveling rack and passed through the apparatus.

At the present time, the standard equipment employed for this purpose consists of one central heater and blower which forces air through sheet iron distributing ducts either over or under the festoon to drive the air against the moist surfaces through small openings in the ducts. This method of drying necessarily requires a rack of great length, that is, between one hundred to two hundred and fifty feet and it has been found impossible to effect individual control due to the fact that the same blower handles the air for a number of racks.

It is, therefore, one of the main objects of the present invention to provide a unit drier which will accomplish the same work in an apparatus of lesser length, approximately thirty-four feet and which at the same time will give individual control.

As a further object the invention contemplates a unit drier, which in addition to the common practice of blowing directly downward into the festoon, includes means for effecting a counter-current course by the employment of deflectors which greatly facilitate the drying operation and materially adds to the efficiency of the apparatus.

As a further object the invention contemplates a unit drier which is subdivided into a plurality of compartments each of which receives the discharged air from the preceding compartment by means of independent blowers for each of said compartments and in which said blowers are actuated by a common driving means to insure that the volume of air handled in each compartment is uniform. This eliminates undue leakage of the heated air through the clearance spaces in the drier housings due to the fact

that the air blasts inside are perfectly balanced.

Furthermore the invention contemplates the employment of a plurality of independent driers preferably superposed with respect to each other and provided with an air duct connecting the same, which duct is provided with automatically operable means for establishing communication between the several driers when in operation or for cutting out those which are not in operation. Under this operation considerable heat is saved due to the fact that the moisture content from the festooned material in the upper drier is extremely small as compared with that of the lower drier.

With the above recited and other objects and advantages in view the invention resides in the novel construction, combination and arrangement of parts set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a side view of a unit drier constructed in accordance with the invention.

Fig. 2 is a sectional plan view taken approximately on the line 2—2 of Fig. 1.

Fig. 3 is an end view.

Fig. 4 is a similar view of the opposite end.

Fig. 5 is a transverse sectional view taken approximately on the line indicated at 5—5 of Fig. 1.

Fig. 6 is a longitudinal sectional view taken approximately on the line 6—6 of Fig. 4.

Fig. 7 is a longitudinal sectional view taken approximately on the line 7—7 of Fig. 4.

Referring to the drawings by characters of reference, 10 and 11 designate respectively upper and lower units which are of substantially identical construction, the same being of rectangular formation. Each unit is divided by a longitudinal vertical partition 12 into parallel passageways which are further subdivided by transverse partitions 13 and 14 into individual compartments 15 and 16. A line or bank of heating pipes 17

extends longitudinally through all of the compartments 15 for a purpose to be hereinafter set forth. The transverse partitions 14 and end walls 18 are provided with 5 aligned openings or doorways 19 through which a traveling rack carrying the festooned material (not illustrated) is adapted to pass. The compartments 15 are provided with intake openings 20 in the end wall 18 10 and the partitions 13. A deflector 21 extends at an angle from a point below the intake opening 20 longitudinally and upwardly to a point immediately below the heating pipes 17 and directly above the 15 intake opening 20 of the next succeeding compartment. The longitudinal partition 12 terminates at its lower end above the bottom wall 22 of the units 10 and 11 with depending portions 23 covering the lower forward side of the deflector plate 21 to provide a space or passage 24 which establishes communication between the portion of the compartments 15 which underlie the deflector plate and the compartments 16. The upper 25 edge of the longitudinal partition 12 terminates below the top wall 25 of the unit to afford passages 26 which establish communication between the upper portion of the compartments 15 and the compartments 16. 30 Longitudinally extending downwardly curved baffles 27 and 28 are secured to the under side of the top wall 25 within the compartments 16. A plurality of staggered longitudinally extending baffles 29 and 30 35 are arranged respectively on the inner side of the outer side wall 31 of each unit and the inner side of the longitudinal partition 12 and disposed longitudinally within the compartments 16. The rear end wall 18 of 40 the upper unit is provided with an outlet opening 32 with which the intake end of a vertical by-pass or duct 33 communicates, the outlet end thereof being connected to and communicating with the intake opening 34 in the end wall 18 of the lower or subter- 45 posed unit 11. The by-pass or duct 33 is provided with a doorway 35 which is normally closed by a gravity actuated door 36 hingedly connected at its upper end as at 37 50 within said doorway. Each of the compartments 15 and 16 of the lower unit are constructed precisely the same as those of the upper unit with the exception that the air in the lower unit is designed to travel counter-current to the air in the upper unit and therefore the deflector plates 21 are reversed. Drive shafts 38 extend longitudinally through the compartments 15 and concentrically through the openings 20 and 32 of 55 the upper unit and the openings 34 and 20 of the lower unit. Each of said drive shafts is connected to a motor or other suitable driving means 39 and has mounted thereon fans or blowers 40 which are arranged respectively within the openings 20, 32 and 34. 60

The first blower 40 arranged in the front end wall 18 of the upper compartment intakes air from the exterior of the upper unit and blows into the first compartment 15. The remaining fans or blowers 40 of the upper unit suck in the air from under the deflector plate 21 of the preceding compartment and blow into the succeeding compartment above the deflector plate with the exception of the rearmost fan or blower which 70 blows into the duct or by-pass 33. The first fan or blower 40 of the lower unit sucks air from the by-pass or duct 33 through the intake opening 34 into the first compartment of said lower unit above the deflector plate 21 while the remaining blowers or fans operate to intake air from under the deflector plate of the preceding unit and discharge 80 above the deflector plate 21 of the succeeding unit with the exception of the last fan or blower 40 which discharges into a moist air discharge pipe 41 communicating with the opening 20 within which said last blower operates. 85

In operation the first blower of the upper 90 unit takes air from an outside source, forces it inside the first compartment against the upper side of the deflector plate 21 where it is projected upwardly against and over the heated surfaces of the pipe banks and thence 95 through the passage 26 against the downwardly curved baffles 27 and 28 into the first compartment 16 and directly downward into the festoons of the material on the traveling rack. During its passage 100 downwardly into said festoons the heated air will move through a sinuous lateral course under the influence of the staggered longitudinally extending baffles or deflectors 29 and 30. At the 105 same time the blower or fan 40 of the succeeding compartment will induce and draw the heated air from the previous compartment under the lower edge of the longitudinal partition 12 through the space or 110 passage 24 and discharge the same into said succeeding compartment where the temperature will be increased by passing over the heating pipes to increase its absorbing capacity. The same operation follows in each 115 succeeding compartment in the upper drier unit until the heated air is finally discharged through the opening 32 into the by-pass or duct 33. By keying all of the blowers to one shaft a uniform result from each 120 blower is obtained, namely, the volume of air handled per compartment of the drier is the same in each case as each succeeding blower, re-handles the same volume of air which the preceding blower started. This 125 eliminates undue leakage of the heated air through the clearance spaces in the drier housings as the air blasts inside are perfectly balanced.

When both sets of blowers are in opera- 130

tion the swinging door or shutter 36 will be maintained by gravity in a vertical position due to the fact that the pressures on both sides are balanced. This permits the 5 heated air in the upper drier unit to pass to the lower drier unit without mixing with outside air. The reason for employing the air duct is that the moisture content in the hanging material 10 passing through the upper unit is very small as compared with that on the rack of the lower unit so that it is found possible to continue the circulation through the lower unit for the purpose of saving considerable 15 heat and effecting real economy. If the lower drier is not in operation the door or shutter 36 will swing and allow the discharge from the upper drier to escape through the doorway 36. When the upper drier is not running and the lower drier 20 is in operation the door or shutter 36 swings inwardly allowing air to be supplied from the interior through the doorway 35. It is thus obvious that the door of the by-pass 25 automatically operates to properly function and carry out the objects of the invention.

In conclusion and to sum up the objects 30 and advantages which are accomplished by the apparatus, it may be briefly stated that the invention of this construction is to remove moisture from materials which have been passed through a coating operation (particularly in the case of wall paper) 35 with the material hanging in festoons on a traveling rack. To this end first the apparatus embodies a unit which includes a plurality of compartments through which the traveling rack and festooned material 40 successively travel and in which compartments the discharged air from the preceding compartment is re-handled and re-heated to increase its temperature and decrease the humidity. Second, the apparatus features 45 means for withdrawing and discharging air successively from preceding compartments into succeeding compartments by means of blower elements that are simultaneously driven at the same rate of speed, 50 preferably by a common driving means. Third, in addition to blowing directly downward into the festoons, the apparatus effects simultaneously the blowing in a sinuous course transversely of the festoon, or 55 in other words causing the air currents to travel downwardly and laterally. Fourth, the principle of employing one or more units in a battery formation by utilizing a by-pass equipped with an automatic door or 60 shutter which operates and functions automatically when one or more of the units are thrown out of operation.

I claim:

1. A drying apparatus embodying a casting 65 including a plurality of compartments

through which a traveling rack carrying the festooned material is adapted to move, means for initially intaking air into the first compartment, means in the succeeding compartments for intaking air from the preceding compartments, means for heating the air taken into said compartments, and means for exhausting the air from the last compartment. 70

2. A drying apparatus embodying a casting 75 including a plurality of compartments through which a traveling rack carrying the festooned material is adapted to move, means for initially intaking air into the first compartment, means in the succeeding compartments for intaking air from the preceding compartments, means for heating the air taken into said compartments, means for exhausting the air from the last compartment, and a common means for actuating 80 the intaking means and exhausting means whereby the same will be driven simultaneously and at the same rate of speed. 85

3. A drying apparatus embodying a casting 90 including a plurality of compartments through which a traveling rack is adapted to move with the material to be dried in festoons thereon, means for initially effecting an intake of air into the first compartment, means in the succeeding compartments 95 for withdrawing the air from the preceding compartments downwardly through the festoons, means for effecting the deflection of the air in a sinuous course through said festoons, means for heating the air in each 100 compartment prior to its contact with the festoons, and means for exhausting the air from the last compartment. 105

4. A drying apparatus including a battery 110 of superposed units each comprising a casting consisting of a plurality of compartments through which a traveling rack supporting the material to be dried in festoons is adapted to move, means for initially intaking the air into the first compartment, 115 means in the succeeding compartments for withdrawing the air from the preceding compartment and effecting its introduction thereinto, means for heating the air in said compartments and means for expelling the air from the last compartment, and a connection between the last compartment of one of the units and the first compartment of the other unit, said connection having an opening therein, and automatically operable 120 means for uncovering the same to discharge or intake through said connection when one of the units is out of operation. 125

5. A drying apparatus embodying a casting, a longitudinally disposed vertical partition therein, transverse partitions subdividing the same into parallel longitudinal series of heating compartments and drying compartments, a heating medium in said heating compartment, a passageway extending 130

through the drying compartments through which the material to be dried, in festooned form on a traveling rack is adapted to pass, said longitudinal partition having an upper passage communicating with the upper portion of the heating compartment and a lower passage communicating with the succeeding heating compartment, and means associated with each heating compartment for inducing a draft of air therethrough and against the heating medium, thence into the drying compartment and finally into the succeeding heating compartment.

6. A drying apparatus embodying a casing, a longitudinally disposed vertical partition therein, transverse partitions subdividing the same into parallel longitudinal series of heating compartments and drying compartments, a heating medium in said heating compartment, a passageway extending through the drying compartments through which the material to be dried, in festooned form on a traveling rack is adapted to pass, said longitudinal partition having an upper passage communicating with the upper portion of the heating compartment and a lower passage communicating with the succeeding heating compartment, means associated with each heating compartment for inducing a draft of air therethrough and against the heating medium, thence into the drying compartment and finally into the succeeding heating compartment, and staggered baffle plates on the opposite side walls of each drying compartment for causing the heated air to travel in a sinuous course through the festooned material.

7. An apparatus of the character described comprising parallel longitudinal rows of heating and drying compartments, each heating and drying compartment having communication with each other at their upper ends and each succeeding heating compartment having communication with the preceding drying compartment at its lower end, heating elements in the heating compartment, means for initially intaking air into the first heating compartment, means in the succeeding heating compartments for intaking air from the preceding drying compartment, and means for expelling the air from the last drying compartment, the said drying compartments having aligned passageways through which the material to be dried is adapted to be passed in festoon form on a traveling rack.

8. An apparatus of the character described comprising parallel longitudinal rows of heating and drying compartments, each heating and drying compartment having communication with each other at their upper ends and each succeeding heating compartment having communication with the preceding drying compartment at its lower end, heating elements in the heating

compartment, means for initially intaking air into the first heating compartment, means in the succeeding heating compartments for intaking air from the preceding drying compartment, means for expelling the air from the last drying compartment, the said drying compartments having aligned passageways through which the material to be dried is adapted to be passed in festoon form on a traveling rack, and a common means for actuating the said intaking and expelling means.

9. An apparatus of the character described comprising parallel longitudinal rows of heating and drying compartments, each heating and drying compartment having communication with each other at their upper ends and each succeeding heating compartment having communication with the preceding drying compartment at its lower end, heating elements in the heating compartment, means for initially intaking air into the first heating compartment, means in the succeeding heating compartments for intaking air from the preceding drying compartment, means for expelling the air from the last drying compartment, the said drying compartments having aligned passageways through which the material to be dried is adapted to be passed in festoon form on a traveling rack, and means in each drying compartment for causing the heated air to travel downwardly in a sinuous course through the festoon.

10. A drying apparatus including a pair of superposed drying units each consisting of parallel rows of longitudinally spaced heating and drying compartments, the drying compartments having communicating aligned passageways through which the material to be dried is passed in festoon formation, heating elements in the heating compartments, means in the first heating compartment for blowing air upwardly therethrough and into the upper portion of the adjacent drying compartment, means in the succeeding heating compartments for drawing the air downwardly through the preceding drying compartment and blowing the same upwardly through said compartment and into the upper portion of the adjacent drying compartment, and means for drawing the air from the last drying compartment and expelling the same therefrom.

11. A drying apparatus including a pair of superposed drying units each consisting of parallel rows of longitudinally spaced heating and drying compartments the drying compartments having communicating aligned passageways through which the material to be dried is passed in festoon formation, heating elements in the heating compartments, means in the first heating compartment for blowing air upwardly therethrough and into the upper portion of the

adjacent drying compartment, means in the succeeding heating compartments for drawing the air downwardly through the preceding drying compartment and blowing the same upwardly through said compartment and into the upper portion of the adjacent drying compartment, means for drawing

the air from the last drying compartment and expelling the same therefrom, and means for causing the air which travels 10 downwardly through the drying compartments to pass through a lateral sinuous course.

LYNN B. CASE.
